SLEEVELESS EXPELLANT HOLDER FOR LIPSTICK OR THE LIKE

Filed Dec. 2, 1942

UNITED STATES PATENT OFFICE

2,419,526

SLEEVELESS EXPELLANT HOLDER FOR
LIPSTICK OR THE LIKE

John W. Anderson, Newtown, Conn.

Application December 2, 1942, Serial No. 467,573

16 Claims. (Cl. 206—56)

1

This invention relates to expellant containers for holding, projecting, retracting and applying bodies or sticks of medicinal, hygienic, cosmetic, marking or other dispensible substances, all of which for convenience herein are exemplified by lipstick.

An important object of the invention is to reduce the thickness of the complete wall structure, which houses and surrounds a lipstick with its carrier, to preferably a single-ply wall forming a simple shell entirely rid of any extra inner sleeve or sleeves surrounding the retracted lipstick and its carrier. Such extra sleeves heretofore have been considered a necessary part of mechanism capable of projecting and retracting the lipstick. Elimination of such extra sleeve enables a lipstick of optimum diameter to be housed within and mechanically projected outward from a container of minimum overall diameter. Viewed conversely, a smaller overall size of housing is enabled to contain and project a lipstick of larger diameter than has heretofore been possible.

Another object is to confine all of the mechanical core parts, which serve to motivate the lipstick carrier, to a location intermediate one end of the outer casing and the nearest end of the carrier.

A further object is to make use of telescoping parts to transmit movement from a hand operated ferrule that is externally exposed for manipulation to a carrier for the lipstick that is slidably lengthwise inside of the casing.

A further object is to shape such telescoping parts to have interengaged flat sides so that they may transmit turning movement to one another while sliding telescopically and without resorting to splines, keys, or the like so that said parts may consist of simple, smooth-walled, tubular members.

A further object is to construct an assembly of such telescopic parts in a manner to limit the extent of operative separation of the parts by means of interengaging flanges at the terminal edges of mutually overlapping tubular members.

A still further object is to assemble interlocking an outside ferrule, exposed for manipulation, with one end of the outer casing so that these parts shall be free for relative rotary movement.

2

The above described and other features of the invention will become clear in greater detail from the following description of representative embodiments, in which description reference is had to the accompanying drawings, wherein:

Fig. 1 shows a holder and container for lipstick incorporating the present improvements held in a single hand of the user in a manner to operate it for projecting, retracting and applying lipstick without assistance from the user's other hand.

Fig. 2 is a view drawn on a much enlarged scale showing the assembled holder and container in vertical central section with the lipstick projecting ready for use.

Fig. 3 shows the parts of Fig. 2 on a reduced scale and collapsed to a position wherein the lipstick is housed within its holder and covered by a usual form of removable cap.

Fig. 4 is an exploded view of the working parts of the stick holder and container before assembly.

Fig. 5 is a view taken in cross section on the plane 5—5 in Fig. 3 looking in the direction of the arrows.

Fig. 6 is a view similar to Fig. 3 showing a modified construction of certain telescoping parts.

The parts shown in the drawings may be composed of any of the many available plastic materials in molded or extruded form, or some or all of such parts may be made of other materials such as metal, or workable paper stock shaped by drawing, stamping or bending sheets thereof, or by casting or otherwise shaping the material to be used.

The outer casing 10, before assembly, is a cylindrical shell open at both ends. Its bottom end is provided with an external annular bead or circumferential flange 11 while its top end is chamfered at 12 to receive the slip-on cover cap 13. A helical groove or thread 19 is sunk in the internal face of casing 10 which groove is dead-ended at 20 near the top of the casing but opens freely out through the bottom end of the casing at 21.

The bottom beaded end of casing 10 seats against an internal annular shoulder 14 formed at the top open end of ferrule 16 and rotatably fits inside the annular rim 15 of such ferrule which rim upon assembly is turned inward all around to imprison or loosely embrace bead 11.

so that ferrule 16 and casing 10 are thereby held together longitudinally and yet free to swivel relatively to each other. The opposite or bottom end of ferrule 16 is closed by an end wall 17 facing the central well 17'. Upstanding fixedly from end wall or cross wall 17 centrally of well 17' there is a driving post 18. In the form here shown, post 18 is square in cross section and hollow to save material, but may be of any preferably polyhedral shape. Ferrule 16 is 10 larger in diameter than casing shell 10 so as to be grasped independently of such shell as shown in Fig. 1.

It is believed to be new in these improvements that the plunger or cup-like carrier 25 for the 15 stick 30 of cosmetic or other applicative substance lies directly next to and slidably fits the helically grooved inner cylindrical surface of the wall of casing 10 and is guided by direct contact therewith throughout the extent of its reciprocative travel lengthwise of the container. Fixed on this carrier is the usual projecting lug 26 which slidably rides in and is guided by helical groove 19 without passing through any sleeve intermediate the carrier and outer casing. Grove 19 and lug 26 are illustrated as one of many varieties of screw thread and follower that might be employed constituting interengaging instrumentalities carried partly by the plunger 25 and partly by the shell 10.

The mechanical parts which act to project and retract the lipstick carrier 25 are herein newly confined to a location between the bottom end of casing 10 and the nearest end of carrier 25. This eliminates what was formerly considered the necessity of interposing a rotatable driving sleeve for lug 26 between the carrier and the adjacent side wall of casing 10 and thus permits substantial reduction in the overall girth or outside diameter of a casing that is capable of holding a lipstick of any given girth or diameter.

In the construction of the carrier actuating parts herein shown, rotation of ferrule 16 is transmitted to carrier 25 in both rotary directions through a telescoping mechanism which may or need not include the longitudinally slidable telescopic tubular coupling 27 which is open at both ends and square in cross section. As shown in Figs. 2, 3 and 5, this coupling slidably overlaps driving post 18 and is in turn slidably overlapped by a hollow shank 28 which depends fixedly from the cylindrical body 29 of carrier 25 and which is square in cross section. The hollow in shank 28 may or need not open at its top end into the cup-like space in cylindrical carrier body 29 in which the lower end of lipstick 30 is seated on the annular internal carrier shoulder 31. However, where lipstick 30 is thus exposed to the hollow in shank 28, the coupling tube 27 if made longer than herein shown may serve to push upwardly on the bottom end of the lipstick and thus act to eject or dislodge a short butt of unconsumed lipstick from its seat in carrier 25 when the parts assume their fully collapsed relationship indicated in Fig. 3.

The extent to which carrier 25 may be moved axially away from driving post 18 is limited jointly by the slide stopping engagement of outward turned lips 35 at the top end of post 18 with inward turned lips 36 at the bottom end of coupling tube 27, and by the slide stopping engagement of outward turned lips 37 at the top end of tubular coupling 27 with the inward turned lips 38 at the bottom end of carrier shank 28. In view of the similarity of the carrier move-

ment to that of a plunger, the carrier is sometimes so referred to herein.

More than one tubular coupling such as 27 having stop lips as 36, 37 may be interposed telescopically between driving post 18 and carrier shank 28, while Fig. 6 shows a modified construction wherein all tubular couplings such as 27 may be omitted and the lengthened shank 28' of the modified carrier 25' made directly to overlap telescopically the lengthened driving post 18' of the modified ferrule 16'. It will be understood that in Fig. 6 the modified carrier 25' is provided with the usual lug 26' riding in the helical groove 19 of the casing 10. The casing can be made proper in length to accommodate the relationship of lengths of post 18' and shank 28' and as dictated by the length of lipstick it is desired to house within the container. Also Fig. 6 illustrates that the driving post and carrier shank may be cylindrical instead of polyhedral, either the post or the shank being provided with a longitudinally extending slot or groove 33 slidably engaged by a tongue-like extension 40. Such groove and tongue may be carried either by the post or by the shank respectively. A corresponding slot and tongue construction may be employed to prevent tubular coupling 27, if made cylindrical, from turning relative to either or both the post or shank.

30 In further possible modifications not shown in the drawings the stepped order of sizes of the telescopically related elements may be reversed, the ferrule post 18 or 18' having the largest cross sectional size and each telescopic part above it 35 having a sufficiently smaller cross sectional size to collapse into positions inside of the post 18' and be overlapped thereby.

The above described parts may conveniently be assembled by preforming the lips 37 and 38 40 which will leave the lips 35 and 36 to be turned over after assemblage.

In operation my improved lipstick holder may be held in the hand of the user somewhat as shown in Fig. 1 with the bottom ferrule clutched between the palm of the hand and the second or third finger, while the thumb and index finger of the same hand is left free to swivel the casing shell 10 about its own axis relatively to ferrule 16. Thus the lipstick can be caused to move back and forth between its projected position in Fig. 2 and its retracted position in Fig. 3. Also with the container so manually held, the extent of projection of the lipstick beyond the open mouth of the casing shell can be maintained or 55 varied while the lipstick is being applied. Other features of the operation will be clear from the foregoing description.

It will be evident to those skilled in the art 60 that parts differing in shape, size and arrangement from those herein shown can be arranged to operate on similar principles and yield the advantages arising from the particular construction herein illustrated to explain the invention and that the appended claims accordingly will be understood to comprehend and to be directed to all fair equivalents for such construction as would be suggested by the disclosure hereof.

The reduction of the complete casing wall 70 structure of a lipstick holder to a single integral thickness is particularly important in holders for lipstick molded from plastic materials because of the somewhat greater thickness of a tubular wall that is necessary where such material is involved.

I claim:

1. In a handle-like applicative container for holding projecting and retracting a body of dispensable substance housed by said container, an elongated open-ended casing shell having a smooth interior cylindrical surface bordering a space within said container, a plunger adapted to carry said body of substance having a smooth cylindrical periphery slidably axially within and filling said space, a ferrule of larger diameter than the maximum girth of said shell exposed for manipulation at one end of said shell and having a central well, interengaging instrumentalities carried partly by said plunger and partly by said shell including a screw thread and a follower therefor, and extensible coupling means within said casing shell connected to be turned by said ferrule in part occupying said well and extending to the nearest end of said plunger and constructed and arranged to maintain said plunger constantly in fixed rotative relation to said ferrule throughout the former's movement lengthwise of said shell.

2. In a handle-like applicative container for holding projecting and retracting a body of dispensable substance housed by said container, an elongated open-ended casing shell provided with an internal helical guide thread and having at its bottom end an external circumferential flange, a plunger adapted to carry said body of substance slidably fitting the inside of said shell and having guiding engagement with said thread thereby to occasion movement of said plunger lengthwise of said shell, a ferrule of larger diameter than the maximum girth of said shell exposed for manipulation at one end of said shell having a central well and provided with an annular rim shaped to embrace said head loosely in a manner to hold said ferrule and casing together while permitting their relative rotation, and extensible coupling means within said casing shell connected to be turned by said ferrule in part occupying said well and extending to the nearest end of said plunger and constructed and arranged to maintain said plunger constantly in fixed rotative relation to said ferrule throughout the former's movement lengthwise of said shell.

3. In a handle-like applicative container for holding projecting and retracting a body of dispensable substance housed by said container, an elongated open-ended casing shell having a smooth interior cylindrical surface bordering a space within said container and provided at its bottom end with an external circumferential flange, a plunger adapted to carry said body of substance having a smooth cylindrical periphery slidably axially within and filling said space, a ferrule of larger diameter than the maximum girth of said shell exposed for manipulation at one end of said shell and having an annular rim shaped to embrace said flange loosely in a manner to hold said casing shell and ferrule together while permitting their relative rotation, interengaging instrumentalities carried partly by said plunger and partly by said shell including a screw thread and a follower therefor, and extensible coupling means within said casing shell connected to be turned by said ferrule and extending to the nearest end of said plunger and constructed and arranged to maintain said plunger constantly in fixed rotative relation to said ferrule throughout the former's movement lengthwise of said shell.

4. In a handle-like applicative container for holding projecting and retracting a body of dis-

pensable substance housed by said container, an elongated open-ended casing shell having a smooth interior cylindrical surface bordering a space within said container and provided at its bottom end with an external circumferential flange, a plunger adapted to carry said body of substance having a smooth cylindrical periphery slidably axially within and filling said space, a ferrule of larger diameter than the maximum girth of said shell exposed for manipulation at one end of said shell having a central well and having an annular rim shaped to embrace said flange loosely in a manner to hold said casing shell and ferrule together while permitting their relative rotation, interengaging instrumentalities carried partly by said plunger and partly by said shell including a screw thread and a follower therefor, and extensible coupling means within said casing shell connected to be turned by said ferrule in part occupying said well and extending to the nearest end of said plunger and constructed and arranged to maintain said plunger constantly in fixed rotative relation to said ferrule throughout the former's movement lengthwise of said shell.

5. In an applicative container adapted to serve as an elongated hollow handle for holding and projecting and retracting axially of said container a contained body of dispensable substance, an elongated open-ended shell including an encompassing wall having a smooth interior cylindrical surface bordering a space within said container receptive to said body, a plunger having a smooth cylindrical periphery slidably axially within and filling said space and having a socket receptive to one end of said body for clinging to and carrying the latter, mutually telescoping members for propelling said plunger axially with respect to said shell located between said plunger seat and one end of said shell, means operatively corelating said telescoping members in a manner positively to restrict their relative rotation while permitting said members to move axially relatively to each other, and interengaging instrumentalities carried partly by said plunger and partly by said shell including a screw thread and a follower therefor.

6. A handle-like applicative container for holding projecting and retracting a stiff stick of solid dispensable substance, embodying in combination, an elongated casing shell having a full open end adapted freely to admit said stick and having a wall with a helical channel sunk therein, said wall presenting a smooth interior cylindrical surface defining the girth of the space for said stick within said container, a cup-shaped plunger slidably lengthwise within said shell carrying a projection riding in said channel said plunger affording a clinging seat for one end of said stick thereby to carry and move said stick in contactable relation to said smooth interior wall surface so that the latter may guidingly maintain the former in lengthwise alignment with said full open end of said casing shell, and telescoping coupling means including relatively nestable members having rectilinear relative bodily movement operatively connecting one end of said shell to the nearest end of said plunger.

7. A handle-like applicative container as defined in claim 6, together with a ferrule member closing the other end of the said shell shaped and disposed outside of the latter to be manually grasped to the exclusion of said shell between one finger and the palm of an operator's hand whereby said shell may be grasped and turned relatively

to said ferrule member by the thumb and another finger of the operator's same hand.

8. In a handle-like applicative container for holding as well as rapidly projecting and retracting a body of dispensible substance housed by said container, an elongated open-ended casing shell having a tubular wall presenting internally a smooth cylindrical face provided with a helical guide thread, a plunger adapted to carry said body of substance having a smooth cylindrical periphery slidably fitting said face of said shell, a circumferentially abbreviated projection laterally outstanding on said plunger periphery having guiding engagement with said thread thereby to occasion movement of said plunger lengthwise of said shell, a ferrule rotatably coupled to said shell and exposed for manipulation at one end of said shell, and extensible coupling means within said casing shell connected to be turned by said ferrule constructed and arranged to drive and maintain said plunger in fixed rotative relation to said ferrule throughout the former's movement lengthwise of said shell.

9. In a handle-like applicative container for holding as well as rapidly projecting and retracting a body of dispensible substance housed by said container, an elongated open-ended casing shell having a tubular wall presenting internally a smooth cylindrical face provided with a helical guide thread, a plunger adapted to carry said body of substance having a smooth cylindrical periphery slidably fitting said face of said shell and having guiding engagement with said thread thereby to occasion movement of said plunger lengthwise of said shell, a ferrule rotatably coupled to said shell and exposed for manipulation at one end of said shell, and extensible coupling means within said casing shell connected to be turned by said ferrule constructed and arranged to drive and maintain said plunger in fixed rotative relation to said ferrule throughout the former's movement lengthwise of said shell, said coupling means further comprising members constructed and arranged to be relatively slidable in a rectilinear path.

10. In an applicative container adapted to serve as an elongated hollow handle for holding as well as projecting and retracting axially thereof a contained body of dispensible substance, an elongated open-ended shell member having a tubular wall with a smooth interior cylindrical face bordering a space within said container receptive to said body, a plunger member having a smooth cylindrical periphery slidable axially within and guidably filling said space and having a socket retainingly receptive to one end of said body, mutually telescoping members for propelling said plunger member rotatably and axially of said shell member located between said plunger seat and one end of said shell, means affording screw engagement between said plunger member and said shell member, and means operatively correlating one of said telescoping members to the other of said telescoping members in a manner positively to restrict relative rotary movement therebetween while freely permitting relative axial sliding movement therebetween.

11. In a handle-like applicative container for holding projecting and retracting a body of dispensible substance housed by said container, an elongated open-ended casing shell provided with an internal helical guide thread, a plunger adapted to carry said body of substance slidably fitting the inside of said shell and having guiding engagement with said thread thereby to oc-

casion movement of said plunger lengthwise of said shell, a ferrule of larger diameter than the maximum girth of said shell exposed for manipulation at one end of said shell and having a central well, and extensible coupling means within said casing shell connected to be turned by said ferrule in part occupying said well and extending to the nearest end of said plunger and constructed and arranged to maintain said plunger constantly in fixed rotative relation to said ferrule throughout the former's movement lengthwise of said shell.

12. In a handle-like applicative container for holding and projecting a body of dispensible substance, an elongated open-ended outer casing shell having an internal helical guide thread and provided at its bottom end with an external circumferential flange, a manually turnable ferrule assembled with said shell at the bottom end thereof having an annular rim shaped to embrace said flange loosely in a manner to hold said casing shell and ferrule together while permitting their relative rotation, a plunger cup adapted to carry said body of substance slidable and rotatable inside of said shell in direct guiding engagement therewith and with said thread, and telescopically related elements having rectilinear relative bodily movement operatively interposed between said manually turnable member and said plunger, one of said elements being connected to be turnable by said ferrule and another one of said elements being connected to turn said plunger.

13. In an expellant lipstick holder and container, the combination of, an open ended cylindrical tubular casing having an internal helical guide thread and provided at its bottom end with an external annular bead, a cap-like ferrule closing said bottom end of the casing having an annular rim shaped to embrace said bead loosely in a manner to hold said ferrule and casing together and permit their relative rotation, a driving post extending to and based fixedly on said ferrule and upstanding therefrom centrally within said casing, a cup-like plunger for carrying said lipstick substantially filling the internal girth of said casing and slidably lengthwise thereof in guiding engagement therewith and having a lug slidably engaged with said guide thread, a driven shank fixedly carried by said plunger and depending therefrom toward said ferrule centrally of said casing, said shank and post being telescopically movable in overlapping relationship, and a tubular coupling so operatively interposed telescopically between said post and said shank that the turning of said ferrule relative to said casing causes said plunger to rotate relative to said casing while said lug and guide thread cause the plunger to slide to various positions lengthwise of said casing.

14. In an expellant lipstick holder and container, the combination defined in claim 13, in which the said tubular coupling is hollow and of size and shape to slide telescopically inside of said driving post and outside of said driven shank.

15. In an expellant lipstick containing holder, the combination of, an open ended casing having an internally threaded tubular wall carrying an external annular bead, a cup-shaped ferrule having a cross wall closing the open end of said casing and having an internal annular groove spaced from said cross wall occupied by said bead, a plunger for carrying lipstick peripherally filling

said tubular casing and slidable lengthwise thereof in guiding engagement with the threaded internal surface of said tubular wall, a post carried by said ferrule having a rotary driving shape extending from said cross wall into said casing and a hollow driven shank fixedly carried by said plunger projecting toward and overlapping and propellingly engaged by said shape of said driving post and telescopically intervening between the latter and said threaded tubular wall of the 10 casing.

16. In an expellant lipstick containing holder, the combination defined in claim 15 in which the said post has a slot extending lengthwise thereof and the said shank has a tongue slidably engaging said slot. 15
